United States Patent Office.

JOSIAH J. PHILBRICK, OF ZANESVILLE, OHIO.

Design No. 3,589, dated July 27, 1869.

DESIGN FOR A BOX.

The Schedule referred to in these Letters Patent and making part of the same.

To all whom it may concern:

Be it known that I, JOSIAH J. PHILBRICK, of Zanesville, in the county of Muskingum, and State of Ohio, have invented a new and useful Improvement in Design for Packing-Boxes; and I do hereby declare that the following is a full, clear, and exact description thereof, which will enable others skilled in the art to make and use the same, reference being had to the accompanying drawings, forming part of this specification.

The object of this invention is to so construct a packing-box that a neat and tasteful recess shall be formed on the end of the box, for the trade-mark or label, and so that said trade-mark or label may be protected from harm in handling the box, in shipping, and transportation; and

The invention consists in beveling the ends of the sides of the box, which are made to project beyond the head or heads, as will be hereinafter more fully described.

Similar letters of reference indicate corresponding parts.

A is the box which is made by nailing the parts together with square joints, as seen in the drawing.

The side pieces B B, and the top and bottom pieces C C, at one end of the box, project and are bevelled off on the inside, as seen at d d, leaving the extreme edge square, as seen at e e.

Upon the end or head F, I design to place the proper label for denoting the contents of the box.

Having thus described my invention,

I claim as new, and desire to secure by Letters Patent—

The design for a packing-box, substantially as herein shown and described.

The above specification of my invention, signed by me, this 28th day of May, 1869.

JOSIAH J. PHILBRICK.
